DESIGN FOR AN AIR-CONDITIONING CABINET

Charles H. Victoreen, Cleveland, Ohio

Application August 1, 1936, Serial No. 64,177

Term of patent 7 years

To all whom it may concern:

Be it known that I, Charles H. Victoreen, a citizen of the United States, residing at Cleveland, in the county of Cuyahoga and State of Ohio, have invented a new, original, and ornamental Design for Air-Conditioning Cabinets, of which the following is a specification, reference being had to the accompanying drawing, forming part thereof.

The figure is a perspective view of a cabinet

showing my new design, the cabinet being laterally symmetrical.

The partial cross-hatching appearing in the upper and lower front panels represents screening which is continuous throughout each of these panels.

I claim:

The ornamental design for an air-conditioning cabinet, as shown and described.

CHARLES H. VICTOREEN.
